UNITED STATES PATENT OFFICE.

JOHN A. KALEY, OF CAREY, OHIO.

TYPE-WRITING MACHINE.

SPECIFICATION forming part of Letters Patent No. 317,371, dated May 5, 1885.

Application filed September 20, 1883. (No model.)

To all whom it may concern:

Be it known that I, JOHN A. KALEY, a citizen of the United States, residing at Carey, in the county of Wyandot and State of Ohio, have invented certain new and useful Improvements in Type-Writers, of which the following is a full, clear, and exact description.

My improvements in type-writers consist in details of construction, and in the combination, arrangement, and operation of parts, as hereinafter set forth and claimed.

In the accompanying drawings, illustrating my invention, in the several figures of which like parts are similarly designated, Figure 1 is a top plan view of the machine complete. Fig. 2 is a top plan view on a larger scale, with the bed-roller, the top plate, and the type-disk removed. Fig. 3 is a rear elevation in the plane of the line $x-x$, Fig. 2, same scale. Fig. 4 is a cross-section on the line $y-y$, Fig. 1, same scale as said Fig. 1. Fig. 5 is a bottom plan view of the type-disk; Fig. 6, a top plan view of the disk-operating cam; Fig. 7, a side elevation of said cam; Fig. 8, a vertical section 25 of the cam; Fig. 9, top and sectional view of the cam-securing washer; Fig. 10, a cross-section of one of the inking-reservoirs; Fig. 11, a detail, partly in section, of a joint for the key-stem and lever; Fig. 12, a partly-sectional plan view of one end of the roller-carriage, showing its gage and the spring-lock bolt for the roller-moving lever. Fig. 13 is a cross-section on the line z , Fig. 1. Fig. 14 is a bottom plan view of one end of the carriage and the adjustable pawl for governing its extent of progression. Fig. 15 is a perspective view 35 of a key or crank to hold the bed-roller in position with relation to the type-disk; Fig. 16, a detail elevation of the break-down roller feed-lever, and Fig. 17 is a side elevation of the bell-hammer trip-piece.

In my invention the types are arranged upon the outer ends of arms radiating from a common center, and as a whole in the general shape of a concave disk, a , of metal, of which a' is the hub, a'' and a''' reinforce therefor, a'' the type-arms, and a^5 a^6 alphabets of small and capital letters, and numerals and punctuation and other marks, arranged in concentric circles at the outer ends of the arms, said arms being springs. The types may be of rubber

cemented to the metal, or they may be of other material and otherwise attached to the arms, or may be one with the arms. The hub of the disk has an angular orifice, a^7 , which matches an angular seat, b' , on the shaft b^2 of the type-disk-moving cam b , so as to rotate with but not upon said cam-shaft, and the disk is detachably connected to said shaft and secured in its seat thereon by a washer, e , having cam surfaces or inclines $c' c'$ binding against projecting pins b^3 b^3 on the cam-shaft b^2 . The washer e has notches c^2 c^2 cut in it, whereby it is set down upon the disk astride the pins b^3 b^3 , and then, being turned a quarter-turn or so, 60 its cam-surfaces $c' c'$ pass under said pins and bind there. A forked wrench to fit the opposite grooves, c^3 c^3 , in the washer may be used to operate the washer. By thus arranging the type-disk a number of disks containing a variety of type may be readily employed on any one machine. The cam proper, b , is a spiral-faced oval plate projecting from the shaft and having a flanged edge, b^4 , forming the acting surfaces of the cam, and slotted vertically at 65 opposite points of the oval or double ellipse, as at b^5 b^5 . The cam-shaft b^2 is slotted vertically, as at b^6 , for a distance about equal to the height of the cam, and in said slot is arranged a lever, d' , pivoted centrally to the shaft, and jointed at 70 its ends are the horizontal members d^2 d^3 , the free ends of which extend out laterally from the shaft and play vertically in the slots b^5 b^5 of the cam. The shaft b^2 is pierced longitudinally in its upper end to receive a gravity-pin, 75 e , rested on or connected with the upper edge of the member d^2 , and similarly pierced in its lower end to receive the pin e' , and said shaft is stepped at each end to fit in suitable bearings for it. The arrangement of this mechanism is such (see Fig. 8) that downward pressure upon the upper edge of the lower member, d^3 , will depress it and elevate the member d^2 , and upward pressure upon the lower or under edge of the upper member, d^2 , will raise it and 80 depress the lower member, d^3 , and these movements are effected through the type-operating keys, as will be hereinafter specified.

Referring to Fig. 4, f is a bridge on the base-plate f' , which forms the lower bearing for the cam-shaft, and f^2 is a segmental plate supported upon posts f^3 , arranged in an arc of a

circle upon the base-plate f' , and equal in number to half the number of type-keys, and spaced to admit the passage between them of the type-keys. The plate f^2 forms a support or stay for the upper end of the cam-shaft, and the type-disk is secured to said shaft above said plate.

The type-operating keys or devices are of several kinds, and may be designated levers of the first and third class, and are such in order to adapt them to the most advantageous disposition of the letters, &c., in straight lines on the key-board. These key-levers have their ends for operating the type-disk shaft grouped about such shaft, and the levers then radiate from this shaft as a center, their ends which have the letter or key stopping at such points, as stated, as to give a rectilinear arrangement of the letters or keys in banks. Those key-levers g whose fulcra g' are at their ends and keys or operating-knobs g'' between their fulcra and acting ends are provided with springs g^3 , which keep their acting ends elevated and in position to act, when depressed, upon the upper edge of the cam b , and those levers h whose fulcra h' are between their acting ends and keys h^2 have springs h^3 , which are arranged to throw said acting ends down, so that when the keys of said levers are depressed their active ends are raised into contact with the under side of the cam. The acting ends of these key-levers extend in between the posts f^3 in pairs—one an upper and the other a lower lever—and thus the series of key-levers are separated from one another in pairs by said posts, and, furthermore, guided thereby in their movement. The cam is so nicely arranged in its bearings and its spirality so adjusted that the striking of its surface by the key or type levers is sufficient to turn said cam to bring the type of the key struck in position for the impression of such type upon the paper, the cam being stopped at the right point by the engagement of the lever of the key struck with the slot in the edge flange of the cam. The transmission of the blow of the key to the type-arm is effected through the member d^2 , pin e , and a hammer, i . This hammer is pivoted at i' over the type-disk upon a hinged shelf, i^2 , and is a lever of the first class. The hinged shelf has a bracket, i^3 , projecting forwardly into the machine and in line with the cam-shaft, for the upper end of which it forms a stay, and the pin e is by the operation of the member d^2 projected up through this bracket, and striking against said hammer i causes its acting end to give a blow to the type-arm beneath it sufficient to make the impression of such type upon the paper beneath it. The type-arms being springs, recover themselves after the key is released. The shelf i^2 is hinged to the frame of the machine so that it and its hammer may be turned aside and disengaged from the type-disk and cam-shaft to permit the removal of the type-disk for repairs or for the substitution of another, or for access to the internal mechanism. The

key board or top of the machine is preferably arranged in banks or steps, substantially as shown, and the key levers radiate from the cam as a center to their knobs, as before stated.

Ink is supplied to the types from ink-reservoirs j , which are removably arranged in the machine upon dovetail bearings or ways j' , brushes j'' within the reservoirs serving to convey the ink and distribute it to the type as the disk is revolved over and in contact therewith. The flanged ways or guides k k' receive the carriage l of the paper-roller bed m . The base l' of the carriage fits in these ways or guides, and its edge next the machine is provided with a toothed rack, l^2 . To lessen friction, said carriage is mounted on rollers l^3 , and to limit its extreme movements it is provided with stops at opposite ends to engage a stop, l^2 , on the bed f' . One of these stops, l^3 , is frictionally though movably held on the base l' , and can be moved to be thrown out of line of the stop l^2 , so as to allow of the entire removal of the carriage from its ways.

To limit the movement of the roller within its extremes—as for printing a short line or on a narrow sheet—I provide an adjustable cam-lever, n , provided with a carrying-frame, n' , on a rod, n^2 , extending longitudinally of and supported in the carriage, so that by moving the frame and lever along the rod to a point where the desired length of line may be obtained the cam-lever is so turned as to bind through its carrying-frame upon the rod, n^3 , and be thereby held at that point, and in the traverse of the roller-carriage said cam-lever will come in contact with the pin n^3 on the way k , and the motion of the carriage be thereby arrested. It will be noticed that this cam-lever binds for motion in both directions. The roller m is of the usual rubber pattern, and is provided at one end with a feed-ratchet, m' , operable in either direction by a reversible gravity or spring pawl, o , which rests upon and slides over the ratchet, and is pivoted to a lever, o' , which has a hand-piece, o^2 . This hand-piece is secured to the lever o' by a slip-joint of any suitable construction, whereby it may be folded more compactly for storage. Such a joint may be composed of a slotted tenon, o^3 , on the handle, (see Fig. 16,) provided with a pin, o^4 , the tenon fitting in a socket, o^5 , in the lever o' , and having a cavity for the pin o^4 , and the handle and lever secured by a transverse pin, o^6 , passing through the slot in the tenon and fixed in the lever, and allowing a longitudinal movement of the handle equal to the length of the pin o^4 , which movement is sufficient to permit the withdrawal and insertion of the pin with respect to the socket-cavity, and consequently the folding of the handle or its rigid alignment with the lever o' . This device I designate a "break-down handle." The extent of movement or rotation of the roller by the engagement of the pawl with the ratchet is controlled by a governor, m^2 , which is a cam-like device pivoted and frictionally held to the head m^3 of the car-

riage and movable toward and from the roller, so as to vary the length of throw the lever may receive, and thereby regulate the number of teeth or the distance the roller may be moved 5 by the pawl in each movement of the lever, and thus the distance between the lines of printing. In Fig. 13 this governor is shown in that position in which the lever o' has its greatest extent of movement, and it is obvious 10 that if the said governor have its free end turned up toward the lever said lever cannot descend beyond the point occupied by said end of the governor. The pawl o is made reversible, in order to provide for the contingency of 15 returning the paper, instead of forwarding it, as to correct errors, &c. Referring to Fig. 13, it will be observed that the handle o^2 is simply a lever pivoted on the shaft of the roller, but movable independently of said roller. Now, 20 in order to reverse the pawl o , if the handle be moved on its pivot in the direction of arrow 1 till the upper edge (marked z^2) of said pawl comes next the tooth just above the tooth with which said pawl is shown in full lines engaged, 25 then said pawl can be swung around or rotated on its pivot into the dotted-line position, when it is operable to rotate the bed-roller in the opposite direction. This reversal of the pawl can be effected, because, when the handle is 30 moved in the direction indicated by arrow 1, it lifts the pawl with it, and when lifted sufficiently the distance between the pawl's pivot and the lower end of the edge o^6 is less than the distance between the pawl's pivot and the 35 point of the tooth on which it rested. After the handle and its pawl have been used to rotate the bed-roller in this position, the handle may be lowered and allowed to rest upon the cam m^2 while the writing or correction proceeds. 40 In some positions of the bed-roller-operating mechanism the pawl o will not automatically engage the teeth of the ratchet m' ; and when in said positions the finger is used to place and hold said pawl against the ratchet 45 until by moving the handle it engages a tooth. The roller is incased next the machine by a metallic shield, m^4 , which shield also serves as a guide for the paper.

m^5 is a movable hold-down and gage for the 50 paper, swung on the shaft of the roller and movable concentrically with the surface of the roller. This gage is swung back as far underneath the printing-disk as it will go to permit the insertion and removal of the paper. Its 55 forward movement is limited by a pin or other stop, b , Fig. 1.

m^6 is a spring pin or bolt arranged transversely of and in the head m^3 of the roller-carriage to limit the range of movement toward 60 the machine of the roller-feeding lever $o\ o'\ o^2$ when in use, and to lock it up between itself and the shield m^4 (see Fig. 1) within the compass of the machine when it is disjointed for storage.

65 The mechanism for imparting a progressive step-by-step feed to the roller-carriage consists of a lever, p , suitably fulcrumed, and

having its free or power end provided with a projection, p' , extending under the bridge f , in which the cam-shaft finds a bearing. This 70 projection p' , and consequently the lever p , is kept normally elevated by a spring, p^2 , Figs. 2 and 3, and serves to receive the lower pin, e' , of the cam-shaft b^2 . The lever p is further provided with a fixed tooth, p^3 , to engage the 75 teeth of the roller-carriage rack, and also with a pivoted tooth, p^4 , moving against a spring, p^5 , which spring holds said tooth normally the distance of one rack-tooth from the tooth p^3 ; but by means of the dog p^6 , pivoted to the 80 tooth p^4 , said tooth may be so moved upon its pivot with respect to the spring as that it will be separated from the tooth p^3 the distance of two of the rack-teeth, as indicated in Fig. 14. In this position the spring p^5 presses on the 85 corners toward the pivots of the parts p^4 and p^6 , and thereby holds them in position. Now, the movement of the key-levers upon the cam, and the consequent rotation of such cam to effect the positioning of the types, and the 90 movement of the lever d' as a result, not only raises pin e to effect the operation of the hammer, but at the same time depresses, through its lower member, d^2 , the pin e' , and it, striking the end p' of the lever p , depresses said lever and causes its teeth $p^3\ p^4$ to so engage the teeth of the rack as to cause the advance of the roller the distance or length of one or two teeth, just as it may be set. The distance is varied in accordance with the work to be done 95 or the spacing required or the type used. The tooth p^4 is recovered or re-engaged with the rack by the spring p^5 . The tooth p^3 serves as a stop to prevent back motion to such rack while freely allowing its forward movement. 100 The movement of the roller-carriage is effected by a spring-fusee, q , on the type-writer frame, Fig. 1, the chain q' of which extends to the handle end of the same and normally tends to draw the roller toward the other end of the 105 machine, or in the direction of printing. The reversal of the carriage is effected manually, the tooth p^4 being disengaged from the rack by a push-rod, r , suitably supported, provided with a spring, r' , to hold it normally 110 retracted, and operated by a bit, r^2 , on a hand-shaft, r^3 , to push said piece against the tooth p^4 and throw and hold it out of engagement with the rack, the spring r' returning the 115 push-piece when released from the hand-shaft r^3 , and the spring p^5 returning the tooth p^4 when released from the push-rod r . By means of this push-rod r and the movable stop b the roller-carriage may be run wholly out of the 120 machine.

The mechanism for automatically notifying the operator when the carriage has run its length consists of a bell, s , suitably supported and struck by a hammer, s' , which is arranged upon a lever-handle, s^2 , pivoted at s^3 to the way or guide k' . This handle has the right-angled portion s^4 , which is then again extended parallel with s^2 , as the end s^4 . This end s^4 extends longitudinally of and over the guide k' , and it 125

and the angle s^4 are shaped to form an incline or cam, substantially as shown in Fig. 3. The handle s^2 is held with its end s^4 down on the guide by a spring, s^5 , and raised to strike the bell by a swing-piece, s^7 , (see Figs. 13 and 17,) pivoted to the head of the carriage. This swing-piece is arranged to pass beneath and against the inclined angle end s^4 of the lever-handle to lift it to move the bell-hammer away from the bell, and when the said swing-piece passes the extreme end of the part s^4 the spring s^5 forcibly throws the hammer against the bell to sound an alarm, and the swing-piece passes over it in the return of the carriage and again drops behind and beneath it.

The guides or ways for the carriage are arranged on the bed f' on arms $t\ t$, which project beneath the key-board, and are movably held to the bed by pins $t\ t'$, passed into the bed through slots $t\ t'$ in the said arms. These arms are provided at their front ends with vertical slotted posts $t\ t'$. A rock-shaft, u , is supported in the front of the machine, or part next the operator, and has crank-arms u' with lateral pins thereon which engage the slotted posts $t\ t'$ in such manner that when the shaft is rocked its cranks will move the arms and their attached carriage nearer to or farther from the type-disk to bring into line either the inner or outer circle of types on the type-arms. The rocking of the shaft is accomplished by depressing the key u^2 , the shank or stem of which is attached to the arm u^3 of said shaft. The spring u^4 , acting against the pin u^5 of the shaft, returns said shaft and the carriage to its position when the key is released. The rock-shaft may be locked in either position by the engagement of the crank or key u^6 with the pin u^7 , this key being a vertical shaft set in the framing and having an operating-handle on the key-board, as indicated at u^8 , Fig. 1, and two bits at opposite edges, (see Fig. 4.) The upper bit engages the said pin u^7 , as shown, in one of the positions of the shaft u , and the lower bit engages it in the other. This latter engagement is made by turning said lower bit in front of said pin u^7 after it has been turned down as far as possible. As the roller-carriage is moved backward and forward the rack-operating mechanism must also be moved. For this purpose the lever p is movably supported on the fulcrum pin p^7 , which passes through a hole in a stud, p^8 , (see Fig. 3,) on the base-plate, and the projection p' slides under the lower end of the pin e' . A spring, p^9 , (see Fig. 2,) holds the rack-operating mechanism against the rack of the carriage in either of the positions of said carriage.

By the employment of the movable carriage and the rock-shaft and its key, I am enabled to bring an upper and lower case type writer within a very small compass, and to have the type-disk of small diameter and the parts greatly compacted. When a large disk is used, the key u^6 is set so that it will engage the pin on the rock-shaft and hold the roller

in proper relation thereto, and so with the small disk, said key holds the roller similarly, but its position is nearer the keys.

The lever p is operable independently of the cam and type-keys, to permit the arbitrary movement of the roller tooth by tooth—as for making spaces. &c.—by means of the bell-crank lever v , pivoted to the post v' and having an arm, v^2 , and knob or push-piece v^3 . The keys $w\ w'$ connect the one with a lever, w^2 , held acting end down below the cam by a spring, and the other with a lever, w^3 , held acting end up above the cam by a spring, and these levers act upon the cam, as do the type-key levers—namely, to turn it; but they are too thick to enter the slots in the cam, and hence do not actuate the arms of the lever d' , their function being to turn the type-disk over 85 the inking-reservoirs to ink the types thoroughly, when they may have become dry from disuse, before printing begins. The slots $b^5\ b^6$ of the cam are a little to one side of the apexes of the same, so that the succeeding key-lever 90 will not impede the egress of its predecessor, and will not strike the point of the cam as a dead-point.

In Fig. 11 I have shown a simple and preferred way of connecting the key or knob stems with their levers, the same being in substance a knuckle-joint, to avoid the use of pins or rivets and to make a more durable connection.

In the arrangement of the key-levers in the 100 framing, instead of all being levers of either the first or third class, it may be necessary to make some as compound levers to get all within the compass of the machine.

As is entirely obvious, slotted joints may be 105 provided in the keys where necessary to get the depression and elevation. The knuckle-joint obviates this.

The rotation of the type-disk to bring the types into position, as desired, and to ink them 110 is effected by the contact of the key-levers with the edge-flange of the cam, and the moment said levers successively strike the arms of the lever d' in said flange the rotation of the type-disk is arrested, and said arms are 115 operated to move the pins $e\ e'$, and through them the type-hammer and the rack pawl or lever p .

The hammer i , instead of being a lever, may be a spring fixed substantially at the point of 120 the pivot or fulcrum of the lever.

The pins $t\ t'$ have heads of less width than the slots t^2 , and said heads normally stand lengthwise across said slots, as at the bottom of Fig. 2, to retain the carriage on the bed, 125 but permitting its adjustment, and said heads may be turned so that their length shall be longitudinal of the slots t^2 , as shown at the upper end of said Fig. 2, to permit the entire removal of the carriage and its appurtenances. 130

What I claim is—

1. A type-disk for type-writers, consisting of the disk of plate metal slotted radially, as shown, to form spring type-bearing arms, and

adapted for ready attachment to and detachment from its rotating mechanism, substantially as shown and described.

2. The type-disk, its supporting-shaft, and 5 a cam on said shaft, combined with key-levers engaging such cam to rotate the shaft to bring the desired type into position, substantially as described.

3. The type-disk, its supporting-shaft, a cam 10 on said shaft, and key-levers engaging such shaft to rotate the shaft to bring the desired type into position, combined with the lever d' , and its attached arms in said shaft operated by said key-levers, a pin actuated by one of 15 said arms, and a type-hammer overhanging the type-disk and operated to strike and depress a type by the raising of said pin by the said arm, substantially as shown and described.

4. The combination, substantially as shown 20 and described, of a type-disk composed of a series of type-bearing arms radiating from a common center, an operating-hammer for said arms, a cam-shaft on which the disk is supported, key-levers for rotating such shaft, a 25 lever, d' , and its attached arms in said shaft operated by said key-levers, a pin in said shaft actuated by one of said arms to cause the hammer to strike the type-arm, and another pin in said shaft actuated by the other of said arms 30 to cause the step-by-step progression of the bed-roller as the writing proceeds.

5. In a type-writer having the type-disk and the cam-shaft with the lever d' and its attached arms, the combination of the movable 35 bed-roller carriage provided with a rack-bar, and the lever p , movably supported to follow the adjustments of the bed-roller carriage and provided with the pivoted tooth p^4 , and the spring p^5 and dog p^6 , to hold the same in its 40 two positions, all substantially as shown and described.

6. In a type-writer, the bed-roller having the ratchet at its end, combined with the break-down handle and the reversible feed-pawl

pivoted thereon, substantially as and for the 45 purpose described.

7. The combination, with the bed-roller feed-pawl, of its bolt or pin for locking it in position, substantially as described.

8. The combination, with the bed-roller, of 50 its carriage, and a stop which can be adjusted to permit the entire withdrawal of the carriage and roller from its ways, substantially as described.

9. The keys or knobs and their levers, combined with a connecting knuckle-joint, substantially as described.

10. The combination, with the type-disk, its cam-shaft and inking mechanism, of levers 60 engaging such shaft to rotate such disk to ink its type independently of the key-levers and type-striking mechanism, substantially as described.

11. In a type-writer, the combination, with the radiating type-arms, the cam-shaft to bring 65 them into position under the action of the key-levers, of said key-levers, having their knobs or keys arranged in parallel right lines, and their levers radiating from the types as a center, substantially as described.

12. In a type-writing machine having the rotating type-disk, substantially as described, the combination, with the bed-roller, its carriage, and ways for such carriage, of the rock-shaft u , connected with the ways of the carriage through the arms t t , and means, substantially as shown, to operate said rock-shaft to place the bed-roller under the different sets of type on the type-disk, and a key or crank 75 to engage the rock-shaft to lock said shaft, as 80 set forth.

In testimony whereof I have hereunto set my hand this 17th day of September, A. D. 1883.

JOHN A. KALEY.
